UNITED STATES PATENT OFFICE.

LA FOREST WHITING, OF BALTIMORE, MARYLAND.

DESIGN FOR A PIPE-SCRAPER.

SPECIFICATION forming part of Design No. 26,063, dated September 22, 1896.

Application filed June 26, 1896. Serial No. 597,089. Term of patent 7 years.

To all whom it may concern:

Be it known that I, LA FOREST WHITING, a citizen of the United States, residing at Baltimore, in the State of Maryland, have invented and produced a new and original Design for Pipe-Scrapers; and I do declare the following to be a full, clear, and exact description of the same, reference being had to the accompanying drawing, forming a part thereof.

The invention relates to a new and original design for pipe-scrapers; and it consists in the peculiar shape or configuration of the scraper.

The design is shown in the accompanying drawing, in which the figure is a perspective view of a pipe-scraper.

The blade A of the scraper is triangular in form and has its edges beveled, as indicated by a, and it is arranged at one end of the handle B, which is placed in alinement with its center, and is disposed at right angles to the length of the said handle, as illustrated.

The handle B is of a circular, or approximately circular, form in cross-section throughout its length, and it is reduced in diameter at a short distance from the blade so as to

form a shoulder b. From this shoulder b to a point c about midway its length the handle B is gradually increased in diameter, and at such point c it is enlarged to form the rounded shoulder d and the diametrically-enlarged portion e at the rear end of the handle, which enlarged portion e has its rear end rounded, as indicated by f.

What I claim is—

The design for a pipe-scraper consisting of the triangular blade arranged at its center upon one end of a handle of circular form in cross-section throughout its length; the said handle having the shoulder adjacent to the blade, the diametrically-enlarged portion e, at its rear end, the rounded shoulder d, at the forward end of the portion e, and the portion c, gradually reduced in diameter from the shoulder d, to the shoulder b, all as herein shown and described.

In testimony whereof I affix my signature in presence of two witnesses.

LA FOREST WHITING.
